United States Patent Office

Des. 232,700
Patented Sept. 10, 1974

232,700

COMBINED BOTTLE AND CAP THEREFOR

John Pardo, Yonkers, N.Y., assignor to The Procter & Gamble Company, Cincinnati, Ohio

Filed Aug. 21, 1972, Ser. No. 282,298

Term of patent 14 years

Int. Cl. D9—01

U.S. Cl. D9—71

FIG. 4FIG. 5FIG. 6FIG. 7FIG. 8

FIG. 1 is an elevational view of a combined bottle and cap therefor showing my new design.

FIG. 2 is an elevational view thereof, as seen from the left of FIG. 1.

FIG. 3 is an elevational view thereof, as seen from the right of FIG. 1.

FIG. 4 is a top plan view thereof.

FIG. 5 is a bottom plan view thereof.

FIG. 6 is a cross sectional view thereof, taken on the line 6—6 of FIG. 1.

FIG. 7 is a fragmentary view similar to FIG. 1 showing the top of the bottle with the cap removed; and

FIG. 8 is a view similar to FIG. 4 showing the top plan view of the bottle with cap removed.

The side opposite that shown in FIG. 1 is the mirror image of the side shown.

I claim:

The ornamental design for a combined bottle and cap therefor, as shown and described.
